Attn: S.

UNITED STATES PATENT OFFICE.

RAY S. HARDIN, OF CHICAGO, ILLINOIS, ASSIGNOR TO BIRTMAN ELECTRIC COMPANY,
OF CHICAGO, ILLINOIS, A CORPORATION OF ILLINOIS.

SWITCH.

Application filed November 16, 1923. Serial No. 675,129.

To all whom it may concern:

Be it known that I, RAY S. HARDIN, a citizen of the United States, residing at Chicago, in the county of Cook and State of Illinois, have invented a new and useful Improvement in Switches, of which the following is a specification.

This invention relates to improvements in switches, and more especially an electric switch. The invention is here shown embodied in a remote control switch. Although I have shown such a switch here as controlled by a manually-operated contact switch, it is obvious that it may be controlled by a thermostat or any other device operating at a distance.

My improved switch may be very easily and cheaply constructed and will be found efficient and quick in operation and very durable. The invention is particularly desirable in connection with a remote control switch such as I have shown, using a solenoid, because in such an apparatus, by the use of only one spiral spring, I am able to furnish a spring counterbalance for the armature of the solenoid and at the same time a spring-pressed and spring-pulled contact to insure a snap make-and-break. Other features and advantages of the invention will appear more fully as I proceed with my specification.

In that form of device embodying the features of my invention shown in the accompanying drawings—

Figure 1 is a view in side elevation of a switch, showing diagrammatically one form of wiring for a remote control, Fig. 2 is an enlarged view of the switch, and Fig. 3 is a view taken as indicated by the line 3 of Fig. 2.

As shown in the drawings, 10 indicates in general any suitable panel, base or support upon which the switch is mounted. The details of the switch itself will be explained hereinafter. 11, 11 indicate wires leading from any suitable source of supply of electrical energy such as, for example, 110-volt A. C. 12 indicates a suitable transformer in order to give a lower voltage such as, for example, six volts for operating the switch. The output of the transformer is carried by the wires 13, 13^a to the solenoid 14 of the switch. In the lead 13^a is placed a manually-operated control switch 15. From

the two wires 11, 11, two leads 16 and 16^a 55 are also taken to any electrical device indicated in general by 17, which, for example, may be a motor. The switch 10 is placed in the lead 16^a in order to cut off or permit flow of current through the motor 17. 60

I will now describe more in detail the switch itself. The solenoid 14 is supported by means of a bracket 18 attached to the panel 10 by means of the screw 19. Below the solenoid there is attached to the panel 10 a rectangular-shaped piece of metal 20 having its two sides 20^a bent up parallel to each other and at right angles to the panel 10. Pivotedly supported between the plates 20^a on the short rotatable shaft 21, is a 70 bell-crank 22 having a long substantially horizontal arm 22^a and a shorter substantially vertical arm 22^b. The arm 22^a carries pivotally attached at its end a vertical core or armature 23, the upper end of which 75 extends up into the electromagnet or solenoid 14. Pivotedly attached at 24, 24 to the plates 20^a is a substantially vertical inverted U-shaped rocker arm 25 which carries on its upper end a downwardly and 80 backwardly projecting contact plate 26. Behind the contact plate 26 is another contact plate 27 mounted on a spring 28 attached to the panel 10 by means of a bolt 29 which forms on its outer end a binding 85 post 30 to which is attached one of the wires 16^a. The other wire 16^a is attached to a binding post 31 which comprises a bolt 32 extending through the panel 10 and holding the plate 20 in place. A loop of wire 90 33 limits the outward rocking movement of the rocker arm 25. A spiral spring 34 connects the upper end of the rocker arm 25 to the upper end of the short arm 22^b of the bell-crank 22. A stop 35 is also provided to limit the downward movement of the armature 23. This armature is somewhat loosely mounted in the solenoid 14 so that free upward and downward movement is permitted without binding or jamming. 95 The upward movement of the armature 23 is limited by engagement of its end 23^a with the bracket 18 at the top of the solenoid. 100

The switch is closed when the contact plates 26 and 27 are in contact, and open 105 when they are separated. In Fig. 2 the switch is shown open by the solid lines and closed by the broken lines. It is to be noted

that when the switch is open the spring 34 connecting the rocker arm 25 and the arm 22^b lies to the left (as viewed in Fig. 2) of the pivot point 24 of the rocker arm; and 5 that when it is closed the spring lies to the right. It will be seen, therefore, that the rocker arm 25, the arm 22^b and the spring 34 act as a sort of toggle arrangement. The spring 34 is of such length that when the 10 switch is open, as shown by the solid lines in Fig. 2, it exerts some pull but not sufficient pull to raise the armature 23 from the stop 35. It does act, however, to a certain extent as a spring counterbalance to the 15 weight of the armature. Accordingly, when current flows through the solenoid 14, the pull of the spring 34 assists the electro-magnetic force in raising the armature from the stop 35. It is known, of course, that the 20 electromagnetic force tending to raise the armature 23 is weakest when the armature is its farthest distance out. For this reason it is very desirable to have the spring 34 give some assistance in raising the armature at 25 this point. When the switch 15 is closed so that current flows through the coil 14, the spring 34 assists in starting the upward movement of the armature 23 which is drawn up into the coil. As the armature is 30 drawn up, the arm 22^b swings to the right (as viewed in Fig. 2) until the spring passes the pivot point 24 when the tension of the spring snaps the rocker arm 25 to the right to bring the contact plate 26 into contact 35 with the plate 27 to close the switch. It is to be noted that when the switch is closed with the parts in the positions shown by the broken lines in Fig. 2, the spring 34 exerts a pull holding the plate 26 against the plate 40 27 to make a firm contact. When in this position, the spring 34 also tends to pull the arm 22^b to the left to lower the armature 23 but when the parts are in this position, the armature is fully up in the solenoid and 45 held firmly by the electromagnetic force and consequently not pulled down by the spring 34. Upon opening of the circuit 13, 13^a, the armature falls so that the arm 22^b rocks to the left until the spring 34 passes the pivot 50 point 24 when it snaps the contact plate 26 away from the contact plate 27.

It is to be particularly noted that the single spiral spring 34 performs three functions. In the first place, when the switch is 55 open it serves to give an initial upward pull to the armature 23 to assist the electro-magnetic force at the start of the movement of the armature. In the second place, as the armature rises and the arm 22^b swings to the right, the spiral spring (upon passing the pivot point 24) serves to snap the plate 60 26 into contact with the plate 27 and press the same into such contact. In the third place, as the switch opens and the arm 22^b swings to the left, the spiral spring (after

it passes the contact point 24) pulls the contact plate 26 away from the plate 27 with a snap.

While I have shown and described certain embodiments of my invention, it is to be understood that it is capable of many modifications. Changes, therefore, in the construction and arrangement may be made without departing from the spirit and scope of the invention as disclosed in the appended 75 claims, in which it is my intention to claim all novelty inherent in my invention as broadly as possible in view of the prior art.

It is to be noted that the upward pull of the spiral spring on the armature assists the electro-magnetic force at the start of the upward movement of the armature and consequently saves current or, in other words, permits the operation of the switch with a smaller current than would be required if the 80 spring did not thus assist the upward movement of the armature. This feature is particularly desirable in connection with switches having remote thermostatic controls. In such switches, it is undesirable and 85 at times, impossible to use a heavy current.

What I claim as new, and desire to secure by Letters Patent, is:

1. In a device of the character described; a contact piece; a terminal electrically connected thereto; a second contact piece mounted on the swinging end of a pivoted rocker arm, whereby said contact pieces may be brought into or out of contact by swinging of said arm; a terminal electrically connected to said second contact piece; a solenoid having an armature movable therein; and a spring connected between said rocker arm and the armature whereby when said armature is in its outer position with respect to the solenoid, said spring exerts a pull on the armature toward the solenoid and a pull on the rocker arm to separate the contacts.

2. In a device of the character described; a contact piece; a terminal electrically connected thereto; a second contact piece mounted on the swinging end of a pivoted rocker arm, whereby said contact pieces may be brought into or out of contact by swinging of said arm; a terminal electrically connected to said second contact piece; a solenoid having an armature movable therein; and a spring connected between said rocker arm and the armature whereby when said armature is in its outer position with respect to the solenoid, said spring exerts a pull on the armature toward the solenoid and a pull on the rocker arm to separate the contacts and when the armature is in its inner position with respect to the solenoid, the spring exerts a pull on the armature away from the solenoid and a pull on the rocker arm to hold the contacts together.

3. In a device of the character described;

a contact piece; a terminal electrically connected thereto; a second contact piece mounted on the swinging end of a pivoted rocker arm, whereby said contact pieces may 5 be brought into or out of contact by swinging of said arm; a terminal electrically connected to said second contact piece; a solenoid having an armature movable therein; a bell-crank having one arm connected to the 10 armature; and a spring connected between the other arm of the bell-crank and the rocker arm, whereby movement of the armature to its outer position with respect to the solenoid causes said spring to exert a pull 15 on the armature toward the solenoid and a pull on the rocker arm to separate the contacts, and movement of the armature to its inner position with respect to the solenoid causes said spring to exert a pull on said 20 armature away from the solenoid and a pull on the rocker arm to hold the contacts together.

4. In combination, a contact piece mounted on the swinging end of a rocker arm; a bell-crank pivotally mounted near the pivot point of said rocker arm, one arm of said bell-crank being movable to either side of the line joining said pivot points; a spring connecting the end of said arm and the 25 swinging end of said rocker arm; a second contact piece lying adjacent the contact piece on the swinging end of said rocker arm; and a stop on the other side of said rocker arm, whereby, when the end of the 30 spring attached to the bell-crank is moved across said line said spring will act to rock said rocker arm to close or separate said contacts; a solenoid having an armature 35 vertically movable therein; a pivotal connection between said armature and the other arm of the bell-crank; whereby said spring operates to exert an upward pull on the 40 armature when it is in its lower position and, at the same time, rock said rocker arm to separate the contacts, and said spring operates to exert a downward pull on said armature when it is in its upper position and, at the same time, pull said rocker arm to hold 45 the contacts together.

5. In combination, a contact piece mounted on the swinging end of a rocker arm; a bell-crank pivotally mounted near the pivot point of said rocker arm, one arm of said bell-crank being movable to either side of the line joining said pivot points; a spring 50 connecting the end of said arm and the swinging end of said rocker arm; a second contact piece lying adjacent the contact piece on the swinging end of said rocker arm and a stop on the other side of said 55 rocker arm, whereby, when the end of the spring attached to the bell-crank is moved across said line said spring will act to rock said rocker arm to close or separate said contacts; a solenoid having an armature 60 vertically movable therein; a pivotal connection between said armature and the other arm of the bell-crank; whereby said spring operates to exert an upward pull on the 65 armature when it is in its lower position and, at the same time, rock said rocker arm to separate the contacts, and said spring operates to exert a downward pull on said armature when it is in its upper position.

5. In combination, a contact piece mounted on the swinging end of a rocker arm; a bell-crank pivotally mounted near the pivot point of said rocker arm, one arm of said bell-crank being movable to either side of the line joining said pivot points; a spring 50 connecting the end of said arm and the swinging end of said rocker arm; a second contact piece lying adjacent the contact piece on the swinging end of said rocker arm and a stop on the other side of said 55 rocker arm, whereby, when the end of the spring attached to the bell-crank is moved across said line said spring will act to rock said rocker arm to close or separate said contacts; a solenoid having an armature 60 vertically movable therein; a pivotal connection between said armature and the other arm of the bell-crank; whereby said spring operates to exert an upward pull on the 65 armature when it is in its lower position and, at the same time, rock said rocker arm to separate the contacts, and said spring operates to exert a downward pull on said armature when it is in its upper position and, at the same time, pull said rocker arm to hold 70 the contacts together.

In witness whereof, I have hereunto set my hand this 14th day of November, 1923.

RAY S. HARDIN.
